The ornamental design for a packaging for a single dose personal care product, as shown and described.

DESCRIPTION

See application file for complete search history.

FIG. 1 is a front perspective view of a packaging for a single dose personal care product, showing our new design;

FIG. 2 is a back perspective view thereof;

FIG. 3 is a front view thereof;

FIG. 4 is a first side elevation view thereof;

FIG. 5 is a back view thereof;

FIG. 6 is a second side elevation view thereof;

FIG. 7 is a third side elevation view thereof; and,

FIG. 8 is a fourth side elevation view thereof.

The evenly spaced broken lines are shown for the purpose of illustrating parts of the article that form no part of the claim.
